CLAIM

The ornamental design for a combined reel caddy and stand for cable spools, as shown and described.

DESCRIPTION

FIG. 1 is a front, side perspective view of a combined reel caddy and stand for cable spools with the inner portion of the opposite side being a mirror image;

FIG. 2 is a top plan view thereof;

FIG. 3 is a side elevation view with the opposite side being a mirror image;

FIG. 4 is a front elevation view thereof;

FIG. 5 is a rear elevation view thereof; and,

FIG. 6 is a bottom plan view thereof.

The handle is shown broken away in FIG. 1 for ease of illustration.

The broken line showing of a spool is for illustrative purposes only and forms no part of the claimed design.

FIG. 1

FIG. 2
